Primary Examiner — T. Chase Nelson(74) *Attorney, Agent, or Firm* — Sterne, Kessler, Goldstein & Fox P.L.L.C.(57) **CLAIM**

The ornamental design for a shoe, as shown and described.

DESCRIPTION

FIG. 1 is a bottom plan view of a shoe showing my new design;

FIG. 2 is a top perspective view thereof;

FIG. 3 is a side view thereof;

FIG. 4 is another side view thereof;

FIG. 5 is a rear view thereof; and,

FIG. 6 is a front view thereof.

The broken lines in the Figures show environment for illustrative purposes only and form no part of the claimed design. The dot-dashed lines in the Figures show the border of the claimed design.

1 Claim, 5 Drawing Sheets# US D685,566 S
